UNITED STATES PATENT OFFICE.

REUBEN H. PLASS, OF NEW YORK, N. Y.

IMPROVEMENT IN GAS-GOVERNORS.

Specification forming part of Letters Patent No. 177,745, dated May 23, 1876; application filed April 21, 1874.

To all whom it may concern:

Be it known that I, REUBEN H. PLASS, of the city, county, and State of New York, have invented certain new and useful Improvements in Gas or Air Governors; and I do hereby declare the following to be a full, clear, and exact description of the same, reference being had to the annexed drawing, making part of this specification, and by which is shown a vertical section through the operative parts of said governor.

My invention relates to that class of gas-regulators in which the movement of a flexible diaphragm regulates the size of the opening through which the gas flows; and my invention consists in constructing the different parts of the regulator as fully described hereafter, to insure greater sensitiveness and accuracy, to facilitate adjustment to suit different pressures, and to render the apparatus more durable, and adapt it for attachment to inlet-pipes occupying different positions.

In the accompanying drawing, which is a sectional elevation of my improved regulator, A is the lower section of the outer casing, being tubular in form at the lower part, where it is provided with three threaded ways or branches, E E' G, and expanded in diameter at the top, to form, with the upper section A², a shallow chamber, F, divided horizontally by a flexible diaphragm, A, the edge of which is clamped between the flanges b b' of the two sections.

The under side of the diaphragm, which may be of leather, rubber, or other suitable material, is protected by a facing of tin-foil or other flexible metallic coating, and through the center of the diaphragm passes the threaded end of a valve-spindle, B, nuts c c upon which bear upon washers d d and clamp the diaphragm between them, and secure the valve-spindle to the same.

The valve-spindle B passes through guides or bearings I J, arranged one above and the other one in a line with the outlet, below a partition, F, dividing the lower portion of the case, and having an opening, D, to which is adapted a valve, C, attached to the spindle. The said valve is of the rounded tapering form shown in the drawing, and has at the lower

edge a horizontal flange, adapted to a seat at the under side of the partition F.

The upper portion of the cap A² is expanded to form a shallow chest, L, which projects over the top of the cap, and has at the under side of the projecting portion one or more openings, f, the said chest being detachable from the cap to permit access to the chamber F, for the purpose of placing upon the diaphragm, or removing therefrom, annular weights H, by which the diaphragm is loaded in accordance with the pressure of the gas.

Between the valve C and the diaphragm the valve-stem B is divided, and provided with a universal joint, h, for the purpose described hereafter.

A screw-plug, K, is adapted to both the branches E E', to either of which the inlet-pipe may be connected, the plug being then inserted in the other, thus rendering the apparatus readily attachable to either vertical or horizontal inlet-pipes. The valve is adjusted and the diaphragm is loaded to permit the free passage of gas at its minimum pressure. As the pressure increases the diaphragm is raised, elevating the valve and contracting the opening, so that as the gas is condensed the volume permitted to pass through the regulator is reduced, insuring a uniform supply to the burners, however the pressure may vary. The loading of the diaphragm by weights H insures a constant pressure thereon, in place of the variable tension which results from the use of springs, as usual.

In order to insure accuracy of operation it is absolutely necessary that the valve shall be maintained central with the valve-opening. It is also necessary that the diaphragm be allowed perfect freedom in its movements—that is, that it be at liberty to rise at one side or the other, which it has a tendency to do under some circumstances—while it is just as essential that there shall be no vertical play or movement of the diaphragm independently of the valve. I effect these results by employing guides above and below the valve, thus maintaining the latter central with the opening, and by making the valve-stem in sections, united by a universal joint, which permits perfect freedom of movement to the

upper section and to the diaphragm, while there is no play between the parts that will alter the relative vertical adjustment of the valve and the diaphragm.

The case L, overhanging the cap A², and perforated beneath, is a most desirable feature of my invention, as thereby the air is admitted above the diaphragm, while the opening is so protected that it cannot be obstructed by dust or dirt falling into it.

I claim—

1. The combination, in a gas-regulator, of the valve-stem B, guided above and below the valve, and consisting of two sections, connected by a universal joint, and a flexible di-

aphragm secured to the upper section of the stem, substantially as and for the purpose set forth.

2. A gas-regulator, the case of which is provided with an outlet-branch, G, and with two inlet-branches, E E', arranged at right angles to each other, and each adapted to receive a detachable plug, K, for the purpose described.

3. The combination of the cap A² and an overhanging casing, L, perforated at its under side, as and for the purpose set forth.

REUBEN H. PLASS.
